C. C. CLYMER

SAFETY SYSTEM FOR ELECTRIC ELEVATORS

Filed Dec. 15, 1926

Inventor:
Charles C. Clymer;
by *Charles C. Clymer*
His Attorney.

UNITED STATES PATENT OFFICE.

CHARLES C. CLYMER, OF SCHENECTADY, NEW YORK, ASSIGNOR TO GENERAL ELECTRIC COMPANY, A CORPORATION OF NEW YORK.

SAFETY SYSTEM FOR ELECTRIC ELEVATORS.

Application filed December 15, 1926. Serial No. 155,062.

My invention is directed to improvements in safety systems for electric elevators for the prevention of accidents due to improper manipulation of an elevator controller in connection with the closing of the elevator door or gate.

Systems have heretofore been provided whereby the elevator motor cannot be energized to effect operation of the elevator in

10 case the elevator door or gate is in its open position, it being necessary that all of the gate contacts be closed before the controller is operated to effect operation of the elevator motor. Systems have also been heretofore provided whereby in case the elevator controller is first moved to an operative position and the gate contacts are afterwards closed by the closing of an elevator door or gate, the elevator motor cannot be energized

20 until after the controller is returned to its off or neutral position. Such former systems have left much to be desired in the direction of simplicity of construction and arrangement, and in the reliability of the operation 25 thereof.

The objects of my invention is to provide an improved system having features of simplicity of construction and arrangement, and reliability of operation for taking care of the 30 above condition, among others.

In carrying my invention into effect in the form which I now regard as the preferred form thereof, I provide a relay which has its winding connected in multiple relation with the winding or windings of the electroresponsive switch mechanism which effects the connection of an elevator motor to its source of supply for the desired direction of operation, and connect this multiple circuit in 40 series relation with a resistor connected in the circuit of the gate contacts. The arrangement is such that in case the elevator controller is first moved to an operative position and the gate contacts are then closed, 45 the resistor will prevent operation of the electroresponsive motor controlling mechanism to connect the motor to its source of supply, and also prevent operation of the relay by limiting the current through the 50 windings of the switch mechanism and the

relay. That will necessitate that the controller be returned to its off or neutral position, thereby opening one of the multiple paths so that the winding of the relay is now connected in series relation with the 55 resistor and the gate contacts, and this relay will then be sufficiently energized to operate and shunt the resistor. If the elevator controller is then moved from its neutral position to an operative position, the windings of the electroresponsive motor controlling mechanism will be sufficiently energized to effect operation thereof. If the gate contacts are all first closed with the motor controller in its neutral position, the relay will 60 operate to shunt the resistor and thus permit operation of the electroresponsive motor controlling switch mechanism when the controller is subsequently operated to an operative position.

Among the advantages of my invention are the following: The scheme is very simple and readily understood by electricians whose duty it is to install and keep electric elevator equipment in operation. The system is readily adaptable to existing systems which either do not have protective arrangements for preventing improper operation of an elevator controller, or for taking the place of apparatus in more complicated systems intended to take care of the general conditions outlined above. Another advantage of the invention is that in case for any reason the governing relay either sticks in its closed position, or the winding thereof is 75 burned out and the relay does not close, a certain measure of protection is nevertheless had since the motor controller is inoperative to effect operation of the elevator until after the gate contacts have been closed.

In the accompanying drawing I have shown a very simplified system of motor control for an electrified elevator, hoist or the like, wherein my invention is incorporated as one of the elements thereof.

Referring to the drawing, the elevator cage 10 is arranged to be operated in the usual manner by means of the electric motor 11, which drives the winding sheave 12. This motor is controlled by means of the car 100

switch 13 which governs the electroresponsive motor controlling switch mechanism indicated as the directional or reversing contactors 14 and 15. The safety relay 16, together with the resistor 17 controlled thereby, are provided for insuring that the controller 13 must be in its neutral position, as indicated, and the gate contacts 18 all closed before either contactor 14 or 15 can be energized to effect operation of motor 11 for either direction of operation of the elevator. It will be observed that the winding of relay 16 is connected in multiple relation with the windings of either the contactor 14 or contactor 15 by the operation of controller 13. It will also be observed that this multiple circuit is included in series relation with the resistor 17 and the gate contacts 18. When the relay 16 operates, it shunts the resistor 17.

As thus constructed and arranged, and with the parts in their respective positions indicated in the drawing, the operation of my invention is as follows: Assume that it is desired to operate the elevator in up direction. The lower gate contact 18 will first be closed by first closing the elevator door or gate, and this will connect the winding of the relay 16 across the supply circuit 19 in series relation with the resistor 17. The value of this resistor is such that with the controller 13 in its neutral position, sufficient current will flow through the winding of relay 16 to effect operation of the relay and the consequent shunting of the resistor 17. If, now, the manually operated controller 13 is moved to its first clockwise position, the directional contactor 15 will be energized to close and connect the motor armature to the source of supply through the contacts of this contactor and the starting resistor 20. This is the proper sequence of operation of the parts in order to effect operation of the elevator. If, instead of that proper operation, the controller 13 is first moved to an operative position, before the lower gate contact 18 is closed, neither the winding of directional contactor 15 nor the winding of relay 16 will receive sufficient energization to effect operation of these devices. That is because of the fact that the winding of contactor 15 and the winding of relay 16 are connected to the same conductor of the source of supply, and when the lower gate contact 18 is closed, these two windings will be in multiple relation with each other and the multiple circuit is in series relation with the resistor 17 and the gate contacts 18. Under these conditions, the resistor 17 will prevent sufficient energization of contactor 15 and relay 16 for operation thereof. If the controller 13 is returned to its neutral position, the circuit through the winding of contactor 15 is open and the winding of relay

16 is now sufficiently energized to effect the closing of the relay and the shunting of the resistor 17 so that when the controller is then moved to an operative position, the contactor 15 will be connected directly across the supply circuit. It will be obvious that the control of the contactor 14 to prevent improper operation thereof is had in the same manner as the control of contactor 15 previously described. In other words, the protective feature of the invention is present to prevent improper operation in either direction of motor operation.

It will be observed that my invention is applicable to existing elevator systems, which have each a manually operable controller and electroresponsive motor controlling switch mechanism, and gate contacts for insuring that the elevator cannot start until after the gate contacts have been closed. It will also be observed that the system is readily applicable for the replacement of more complicated and less reliable systems previously installed for accomplishing the general purpose. A further feature is that in case any gate or door contacts are opened after the elevator is in operation, the relay 16 and the selected directional contactor will be immediately opened and the elevator stopped. If the relay 16 is closed, the controller 13 being in its neutral position, and any gate or door contacts are opened, the relay will immediately open, thus preventing unsafe operation.

What I claim as new and desire to secure by Letters Patent of the United States is:

1. In combination in a safety system for the control of electric elevators, electroresponsive reversing switch mechanism for controlling the direction of operation of the elevator, a reversing manual controller for controlling said switch mechanism, a safety electromagnetic relay, a resistor, gate contacts, and electrical connections between said controller, the operating windings of said switch mechanism, the winding of said relay, and said resistor whereby the resistor prevents sufficient energization of said reversing switch mechanism for operation thereof in case said gate contacts are closed after said controller is operated to an elevator operative position, thereby necessitating the return of said controller to a neutral position to effect sufficient energization of said relay to shunt said resistor and permit sufficient energization of said switch mechanism for operation thereof when said controller is subsequently operated to an elevator operative position with the said gate contacts maintained closed.

2. In combination in a safety system for electric elevators, an electric motor for operating the elevator, electromagnetic switch mechanism for controlling the connection

of said motor to a source of supply, a manual controller for said switch mechanism, a circuit including the winding of a safety electromagnetic relay, a resistor and 5 gate contacts in series relation across said source of supply, the operating winding of said switch mechanism being connected to be included in multiple relation with the winding of said relay when said controller 10 is in an operative position, whereby in case said gate contacts are closed after said controller is operated to an operative position, said resistor prevents sufficient energization of said switch mechanism and said relay for operation thereof, thereby necessitating 15 the return of said controller to a neutral position to permit said relay to shunt said resistor.

In witness whereof I have hereunto set my hand this 14th day of December, 1926.

CHARLES C. CLYMER.
